UNITED STATES PATENT OFFICE.

DANTE D. PORSI AND CONO RODINO, OF UNION CITY, NEW JERSEY.

HEEL FOR BOOTS OR SHOES.

Application filed March 2, 1927. Serial No. 172,049.

This invention relates to improvements in shoe heels and especially wooden heels carrying an exterior covering of fabric, leather or similar material.

- 5 Wooden shoe heels are usually covered with an exterior covering which is turned in at the bottom of the heel, the latter having attached thereto a leather or rubber lift which receives the wear in contact with the tread surface. When the leather lift wears out, the lower portion of the heel covering and the heel itself, receives the wear. The heel covering of satin, leather, or other fabric at the lower edge of the heel thereby becomes 10 worn, breaks through and is ruined, and the lower edge of the wooden heel, itself, begins to split and chip, necessitating a total discarding of the heel and its replacement by a new one.
- 15 It is an object of this invention to prevent the wooden heel and its covering from receiving the wear when the heel lift wears out by providing a protecting metal plate. Another object of the invention is to fasten 20 the protecting metal plate to the heel covering and the heel at a plurality of points to hold the fabric covering in a secure and immovable position, thereby preventing air pockets which under the pressure created by 25 walking, tend eventually to force air between the heel and fabric, forming a balloon-like effect, destroying the continuity of the fabric covering and disintegrating the wooden heel, eventually forcing the fabric to give away.
- 30 Another object of this invention is to provide simple, efficient and economical means for manufacturing the protecting metal plate.

- Broadly, the invention comprises the production, as a new article of manufacture, of 35 a stamped metal plate adapted to be attached to a heel to prevent the heel and its covering from wearing out. More specifically, the invention contemplates, as a new article of manufacture, a heel having a fabric covering turned in at the bottom surface of the heel to form a facing and a protecting metal plate made from a malleable metal comprising an exterior member having the configuration of 40 the heel and a flange member integral with the exterior member embracing the facing and heel bottom to protect the same from wear. The malleable metal protecting plate is provided with a number of teeth capable 45 of being bent over and fastening the turned-

50 in fabric facing resting against the bottom of the heel substantially immovably in place.

The invention accordingly consists in the features of construction, the combination of elements and arrangement of parts which 55 will be exemplified in the construction hereinafter set forth and the scope of the application thereof will be indicated in the following claims.

The invention is illustrated in its preferred embodiment in the accompanying drawing wherein:

Figure 1 is a side view of a heel carrying the protecting metal plate;

Figure 2 is a sectional view thereof;

Figure 3 is a plan view of the protecting metal plate with fastening members provided with a plurality of teeth or claws adapted to be bent over and plunged into the fabric facing resting on the bottom surface of the heel or through the fabric facing and fastened to the bottom of the heel;

Figure 4 is a sectional view showing the teeth or claws of the metal protecting plate plunged into the fabric to fasten the same to the bottom of the heel;

Figure 5 is a side view of a modification wherein the metal plate is provided with holes for fastening the plate to the heel;

Figure 6 is a side view of a heel carrying a metal plate provided with an extending tongue;

Figure 7 is a sectional view showing the teeth or claws of the metal plate plunged through the heel fabric and into the bottom of the heel;

Figure 8 is a perspective view of the protecting metal plate; and

Figure 9 is a bottom plan view of the heel having attached thereto the protecting metal plate.

Referring to the drawing, the heel 1 carrying the covering 2 is provided with a metal protecting plate 3 and a lift 4 which may be made of any suitable natural or artificial material such as leather, rubber, or a synthetic composition. The fabric covering 2 covers the entire outer surface of the heel 1 and is turned in at the lower extremity thereof to provide a fabric selvage or facing 9, as indicated in Figures 4 and 7. The metal plate 3 is shaped to conform to the lower portion of the heel and comprises a vertical wall 5 and a turned in flange 6 provided with a plurality of fastening members 100 105 110

7 having teeth or claws 8 adapted to be plunged into the fabric selvage or facing 9 at a plurality of points, as indicated in Figure 4. In this form of the invention the 5 teeth 8 do not entirely penetrate the fabric selvage or facing. In the modification shown in Figure 7, the teeth 8 not only penetrate the fabric selvage or facing 9, but are plunged into the heel bottom 10, thereby fastening the selvage or facing to the bottom 10 of the heel at a plurality of points in a secure and immovable position.

Either arrangement functions to prevent the fabric covering 2 from becoming worn 15 or the heel bottom 10 from chipping or splitting when the lift 4 is worn out. It is desired to point out that although it has heretofore been proposed to protect heel bottoms with metal plates, the plates are constructed 20 differently from the plates herein set forth, function differently and are inherently defective in that all of them allow the formation of air pockets. Due to the pressure created by walking, the plates heretofore used allowed air to be forced between the heel and the fabric, causing the fabric to assume a balloon-like effect. This is greatly intensified on damp days as the air is saturated with moisture and carries the 25 same to the fabric covering at the lower portion of the heel. A similar effect results from the immersion of the heel on wet days in water. According to the present invention, the fabric facing or selvage 9 is se- 30 curedly and immovably fixed at a plurality of points, entirely preventing or minimizing the formation of air pockets and the production of a balloon-like effect, due to the air pockets, or contact with water. Additionally, the present invention possesses the 35 advantage of a quick and simple integral attaching means. It is only necessary after the plate 3 has been applied to the heel 1 to slightly bend over the fastening members 40 7 and insert the teeth 8 into the fabric fac- 45 ing or selvage 9 or through the selvage and into the heel bottom 10. The invention herein set forth has the further advantage of simplicity. The heel plate 3 may be 50 stamped out of any suitable metal, such as copper or copper alloys suitably treated so as to adapt them to a stamping treatment. In this connection it may be stated that the invention is not limited to the use of copper

as the plate material. Galvanized iron, 55 which is also resistant to atmospheric corrosion, may be used. Broadly, use is contemplated of any metals or alloy which adapts itself to stamping. It is, of course, clear that instead of a galvanized rust-proof coating, any rust-proofing means may be employed, as, for example, nickel or chromium plating.

The metal plate 3, when fitted tightly against the lower outside covering 2, may be additionally fastened to the inside face of the heel by nails 12, as shown in Figure 1. However, it is preferred to fasten the metal plate 3 to the outside lower portion of the heel at a plurality of points, as indicated in Figure 5, which shows holes 13 adapted to receive fastening nails.

The plate 3 may be plain or ornamental to give a pleasing, artistic appearance. For example, the plate may be escalloped, as indicated at 14 in Figures 1 and 5.

In order to protect the fabric covering inside of the heel, which is usually made from cheaper fabric than the outside, an extending tongue 15 may be made integral with 70 the metal plate, as indicated in Figure 6.

The metal protecting plate herein set forth is applied primarily to wooden heels, but obviously the invention is clearly applicable to heels made from other natural 85 or synthetic products.

We claim:

1. As a new article of manufacture, a heel having a covering material turned in at the bottom surface of the heel to form a facing, 90 and a protecting metal plate comprising an exterior member having the configuration of the heel, and a flange member provided with teeth to hold said facing and covering material substantially immovably in place.

2. As a new article of manufacture, a heel having a covering material turned in at the bottom of the heel to form a facing, and a malleable protecting plate comprising an exterior member having the configuration of 100 the heel and a flange member provided with bent teeth engaging said facing and fastening said facing and covering material substantially immovably in place.

In testimony whereof we hereunto affix 105 our signatures.

DANTE D. PORSI.
CONO RODINO.
